UNITED STATES PATENT OFFICE

171,612

PORTABLE HEAVY-DUTY WEIGHING SCALE

Leslie R. Murphy, Sacramento, Calif.

Application November 6, 1952, Serial No. 22,154

Term of patent 14 years

(Cl. D52—10)

To all whom it may concern:

Be it known that I, Leslie R. Murphy, a citizen of the United States, residing at Sacramento, State of California, have invented a new, original, and ornamental Design for Portable Heavy-Duty Weighing Scale, of which the following is a specification, reference being had to the accompanying drawing forming a part hereof.

Fig. 1 is a view in end elevation of a portable heavy-duty weighing scale with the ramps shown in lowered position, illustrating my new design.

Fig. 2 is a view in end elevation of the same scale, looking from the opposite direction and with the ramps raised into their upper position, where they are placed when the scale is moved from place to place.

Fig. 3 is a view in side elevation of the scale shown in the same position as in Fig. 2; and Fig. 4 is a top plan view of the scale shown in the same position as in Fig. 2.

I claim:

The ornamental design for a portable heavy-duty weighing scale, substantially as shown.

LESLIE R. MURPHY.
